UNITED STATES PATENT OFFICE.

HOWARD E. PETRO, OF SALT LAKE CITY, UTAH.

ORE-CONCENTRATING APPARATUS.

Application filed June 26, 1925. Serial No. 39,746.

This invention relates generally to apparatus for concentrating and separating valuable mineral products from waste materials, but relates more particularly to that type of concentrating apparatus wherein an oscillating concentrating pan is employed as distinguished from jigs, shaking-tables, and the like.

One object of the invention is to provide a concentrating apparatus wherein an oscillating concentrating pan may be reciprocated in a vertical path, whereby to more completely and thoroughly separate the mineral products from the waste materials.

Another object of the invention is to provide means for regulating and varying the range of both the vertical reciprocation and the horizontal oscillation.

A further object of the invention is to provide a concentrator of the type described; wherein the oscillating pan derives a simultaneous vertical reciprocation by reason of its manner of support rather than by some auxiliary mechanical means.

A further object of the invention is to provide a concentrating apparatus wherein the valuable mineral products may be removed from the apparatus at a point where the agitation of the material is greatest, and wherein the waste materials are removed at a point where the agitation is least.

With these objects in view the invention, broadly stated, consists in suitable supports from which a concentrating pan is suspended by means of flexible cables. Suitable power means are employed to oscillate the pan about a vertical axis, which movement, due to the flexible suspension of the pan, gives the latter a simultaneous vertical reciprocation, a single bearing member being employed to confine the pan against the lateral movement during said oscillation and reciprocation.

One embodiment of the invention is fully described in the following specification and illustrated in the accompanying drawings, in which

Figure 1 is a perspective view of the apparatus.

Figure 2 is a fragmental detail plan view 50 of the concentrating pan operating mechanism.

Figure 3 is a fragmental vertical elevation, partly in section, of the pan and the power drive therefor. 55

Figure 4 is a detail view, partly in section, of one of the discharge spigots.

Figure 5 is a detail view, partly in section, of one end of the discharge conveyor.

Figure 6 is a detail view, partly in section, 60 of one of the adjustable supporting elements.

Referring more in detail to the accompanying drawings, in which like reference characters are used to designate like parts throughout, the numeral 1 designates a plurality of piers or abutments of any desired size and configuration, and designed to support the upright standards 2, which are connected together at their upper extremities by means of cross beams generally indicated by 70 the numeral 3. The uprights 2 and the cross beams 3 may be connected together in any manner desired, such as for instance, by rivets, welding, or the like, and said members are preferably braced by inclined strut members 4, whereby to provide a substantial and rugged supporting frame work for the concentrating apparatus. The cross beams 3 are each preferably composed of a pair of channel irons 3^a, secured together in spaced 80 relation with the webs of the channels positioned back to back, thus forming open slots or channel ways 5, running throughout the length of the fabricated beams. This construction is clearly shown in Figures 1 and 6. 85

The concentrating pan generally indicated by the numeral 6 is suspended from said overhead beams 3 by means of a plurality of flexible cables 7, said cables being secured to the beams 3 and to the pan 6 through the 90 instrumentality of eye-bolts 8 and 9, respectively. The eye-bolts 8 are mounted in the open slots 5 of the cross-beams 3, and are adjustable longitudinally thereof by means of clamping plates 8^a carried by the bolts and engaging the upper and lower faces of said beams, said plates being adapted to be securely clamped to the beams at any desired 95

point by means of jam nuts 10; whereas, the eye-bolts 9 may be secured in any suitable manner to the upper rim of the pan 6.

The construction of the concentrating pan 6 is best disclosed in Figure 3, wherein is shown a cylindrical container or pan having a flat bottom 11 and a relatively deep straight side wall 12. A settling ring or baffle 13 is shown mounted concentrically within the pan and supported in spaced relation with respect to the bottom and side wall thereof by means of supporting and spacing members or brackets 14. The ring supporting members may be riveted or otherwise fixedly secured to the ring and side wall of the pan and, if desired, may also serve as means to which the eye-bolts 9 are secured, it being noted, however, that, if desired, the eye-bolts may be cast or otherwise formed integral with the ring supporting members. It is to be further noted that the settling ring 13 is not of the same depth throughout its length, but is preferably graduated in depth from a high point 13^a to a low point 13^b, thus forming a uniformly varying classifying passage between the bottom edge of the ring and the bottom of the pan 13, for the purpose of enhancing the separation of the mineral from the waste materials.

The pan 6 may be of any suitable material, such as heavy gauge sheet metal, and is preferably provided with an auxiliary wear plate 14 of cast iron, said plate being slightly arched or convex for the purpose of aiding the separation of the materials being worked. The bottom 11 of the pan is provided with a plurality of discharge orifices 15, positioned adjacent the periphery thereof for permitting the removal or discharge of the mineral products recovered. The wear plate 14, if desired, may be provided with apertures 14^a, adapted to register with the apertures 15 of the pan, to facilitate the ready egress of the mineral products. The orifices 15 are controlled by suitable gates or spigots 16 which, as shown in Figure 4, are pivotally secured to the bottom of the pan by means of stud bolts 17. Coil springs 17^a are associated with each stud bolt for the purpose of confining the gates or spigots 16 tightly against the under surface of the pan, but, at the same time allowing free manipulation of said gates by means of suitably provided operating members 18. It is apparent from Figure 4 that the gates 16 may be in the form of flat plates suitably apertured as at 19 and adapted to be turned about the stud bolts 17 as pivots to bring the apertures 19 of the gates into partial or total registration with the apertures 15 in the bottom of the pan to thereby regulate the rate of discharge of the mineral products from the pan. Any desired number of the discharge orifices 15 and control gates

16 may be provided, the embodiment illustrated in the drawings being equipped with four of such devices.

As hereinbefore indicated, the concentrating pan 6 is designed to be oscillated about a vertical axis to bring about the separation of the material it contains, and to this end a central pier or abutment 20 is provided beneath the pan and upon which is mounted a single vertical bearing 20^a, said bearing being designed to receive a short spindle or shaft 21 carried by the bottom of the pan 6. The spindle 21 of the pan is disposed concentrically of the pan on the outside of the bottom thereof, and projects axially therefrom into the bearing 20^a, said spindle being provided with a flange 22 by which said spindle may be secured to the pan bottom by bolts, rivets, or any other suitable securing devices. 85

Suitable power means to oscillate the pan is provided in the form of a rotating crank 23 and pitman 24. The crank 23 is driven by means of bevelled gears 25 and 26, the gear 25 being secured to the crank shaft 25^a mounted upon a suitable pier or abutment 1^a in a vertically disposed bearing 25^b, whereas the gear 26 is secured to a countershaft 27 carrying suitable drive pulleys 28. The crank 23 is connected by pitman 24 to the bottom of the pan 6, said bottom for this purpose being provided with a ball stud 29 for engagement with a split ball socket 30, carried by the pan end of the pitman. The crank 23 is provided with a ball pin 31 for engagement with a split socket 32 carried by the crank end of the pitman, said crank pin 31 being adjustable with respect to the crank through the instrumentality of longitudinally distributed apertures 23^a, provided in said crank whereby to regulate and adjust the throw of the crank and the resulting degree of oscillation of the pan. 100

An inclined supply chute or trough 33 communicating with a suitable source of supply delivers material to the pan at a point between the side wall thereof and the inner settling ring 13. Upon operation of the pan, as will be hereinafter described, the material is separated into waste and mineral, the latter flowing to the outer edge of the pan bottom and being discharged through the orifices 15, whereas the waste passes down between the rim and side wall of the pan, under the rim, and thence upwardly along the arched wear plate to the center of the pan. For the purpose of removing the waste material collecting in the center of the pan, an endless conveyor generally indicated at 34, is provided, said conveyor being mounted for pivotal movement about a shaft 35, mounted diagonally upon the cross beams 3. The conveyor 34 comprises a pair of spaced longitudinal beams 36 carrying a rotatable shaft 37 at their adjacent free 115

ends, said shaft carrying a pulley 38, which, together with a pulley 39, carried by the shaft 35, provides a supporting and driving means for the conveyor belt 40. The belt 40 is provided with a series of suitable buckets 41 which are preferably perforated as at 41^a; whereby to permit the working fluid entrapped in said buckets to drain back into the concentrating pan. If desired, the shaft 37 may be adjustably mounted in the beams 36, as shown in Figure 5, for the purpose of adjusting the tension of the belt 40.

The shaft 35 and conveyor 34 are driven from the countershaft 37 by means of a belt 42, thus utilizing a single source of power to drive both the concentrating pan and the waste removal conveyor. The conveyor 34, by reason of its pivotal movement about the shaft 35, may be adjustably positioned with respect to the concentrating pan, and to secure the conveyor in any desired position, suitable means such as a cable 43 may be employed.

From the foregoing description it is apparent that the entire weight of the concentrating pan and contents are supported from above by means of the cables 7. It is also apparent that the pan, when oscillated by the pitman 24, will, due to the partial twisting and untwisting of the cables 7, be given a vertical reciprocation of an extent to be determined by the position of the eye-bolts 8 with respect to the point of intersection 44 of the cross beams 3, and also the degree of oscillation of the pan, the single vertical bearing 20^a serving not only to prevent lateral displacement of the pan due to the motion of the pitman, but also to confine the vertical reciprocation of the pan to a vertical path. It is to be noted that the throw of the crank 23 is so timed with respect to the vertical reciprocation of the pan that the dead center points between the crank and pan occur at points of maximum elevation of the pan, whereby the gravitational pull upon the pan may be utilized to carry the crank past both dead center points. This feature is clearly illustrated in Figure 2, which shows the pan in its lowermost position or its normal position of rest.

The operation of the device is as follows: The eye-bolts 8, the conveyor 34, and the crank pin 31 having been adjusted in accordance with the material to be worked, the apparatus is put in motion and material supplied to the pan by the chute 33 between the settling ring 13 and the side wall 12 of the pan. Due to the combined oscillation and reciprocation of the pan, as described, the material is regularly and periodically agitated by a combined centrifugal and up and down movement which causes the heavy and valuable products to be forced to the periphery of the bottom 11 of the pan to be there

discharged through the orifices 15, while the lighter and waste materials work down under the settling ring and up into the center of the pan where they are removed by the conveyor 34. It is to be noted in this connection that the raw material is fed to the pan at a point where the agitation is greatest, the waste material being removed from the center of the pan where the agitation is least, this manner of supplying material to the pan and removing the waste therefrom insuring the greatest possible percentage of recovery. It is to be further noted that the material being worked is charged into the pan at a point between the pan rim and the settling ring and preferably at the point where the ring is of greatest depth. As the pan is oscillated clockwise and counterclockwise, the material is gradually shifted from this point in either direction, due principally to its own inertia, functioning as the direction of rotation of the pan is reversed. This movement, coupled with the simultaneous rise and fall of the pan, brings the larger portions of the mass to the top and to points most remote from the point of maximum depth of the ring. The tapered formation of the ring 13 permits the larger portions of the waste material to pass readily under the ring at those points at which said material will naturally accumulate.

The valuable products separated from the waste and discharged from the pan through the orifices 15, are received by the usual concentrate launder 45. In order to regulate the rate of discharge the valves 15 are manually adjusted to bring the apertures of the gates thereof into total or partial registration with orifices 15, or, if desired, the gates 16 may be provided with a plurality of apertures varying in size so that any one of said apertures may be placed in registration with an orifice 15 to vary the rate of discharge from the pan. The waste material removed by the conveyor 34 may be discharged upon an overhead lateral conveyor (not shown) to be discharged in any convenient point.

In conclusion, it is to be noted that while a preferred embodiment of the invention has been herein described and illustrated, such description and illustration is for the purpose of example only and not as defining the limits of the invention, which are to be determined by the scope of the appended claims.

Having thus described the invention, what is claimed as new is:

1. A concentrating apparatus comprising a pan, a spindle carried by the pan, a guide bearing, said spindle being slideable and rotatable within the bearing, a support overlying the pan, flexible means for suspending the pan from the support, and means to oscillate the pan about the spindle as an

axis, the points of suspension of the pan on the support being fixed against angular movement with respect to the axis of oscillation whereby to impart to the pan a simultaneous movement of vertical reciprocation.

2. The apparatus described in claim 1 wherein adjustable means are included between the flexible suspension means and the support whereby the points of suspension of the pan with respect to the support may be varied to alter the range of vertical reciprocation of the pan.

3. In a concentrating apparatus, a concentrating pan comprising a flat bottom and a cylindrical side wall, a settling ring mounted within the pan above the bottom thereof, said ring being of varying depth and spaced from the side wall of the pan whereby to produce an annular chamber communicating with the center of the pan by means of an annular opening of varying cross-sectional area.

4. A concentrating apparatus comprising a concentrating pan, means for constraining the concentrating pan to rotary and vertical sliding movement about a fixed axis, a support having members overlying the pan, longitudinally inelastic and laterally flexible supporting elements having their upper ends secured to the supporting members and their lower ends secured to the pan at spaced points around the periphery thereof and means for oscillating the pan, the points of suspension of the pan on the support being fixed against angular movement with respect to the axis of oscillation whereby the same will also be simultaneously reciprocated.

5. The apparatus described in claim 4, wherein the pan oscillating means includes a flexible power connection whereby the pan may be positively and continuously oscillated throughout the range of its vertical reciprocation.

45 6. A concentrating pan including an annular baffle mounted therein in spaced relation to the sides and bottom of the pan and defining a material receiving compartment between the baffle and pan sides, said baffle being of varying depth and defining a classifying passage, tapered in cross-sectional area, between the baffle and the bottom of the pan.

55 7. A concentrating apparatus comprising a concentrating pan, a support, means to flexibly suspend the pan from the support, guide means to constrain the pan against lateral movement, and means to rotarily oscillate the pan about a vertical axis, the pan suspension means being secured to the support and fixed against angular displacement with respect to the axis of oscillation of the pan whereby upon oscillation of the pan said flexible suspension means are alter-

nately inclined with respect to the support 65 to alternately raise and lower the pan.

8. The apparatus described in claim 7, wherein the pan carries a spindle, and wherein the guide means comprises a bearing engaging the spindle to confine the rotary oscillation of the pan to a fixed axis 70 extending through said spindle.

9. The apparatus described in claim 7, wherein the pan suspension means are flexible non-extensible members whereby a 75 simultaneous movement of vertical reciprocation is imparted to the pan due to the twisting and untwisting of the flexible suspension members when the pan is rotarily oscillated.

80 10. A concentrating apparatus comprising a concentrating pan, a support, means to flexibly suspend the pan from the support, a spindle carried by the pan, a bearing engaging the spindle, said spindle and bearing being capable of relative sliding and rotary movement, and power means to oscillate the pan about an axis extending through the spindle, the points of suspension of the pan on the support being fixed against angular displacement with respect to the axis of oscillation of the pan whereby to impart movement of rotary oscillation and vertical rectilinear reciprocation to the pan.

85 11. A concentrating apparatus comprising a concentrating pan, a support, means to flexibly suspend the pan from the support, and power means to rotarily oscillate the pan about a fixed vertical axis, the points of suspension of the pan on the support being fixed against angular displacement with respect to the axis of oscillation of the pan whereby to simultaneously reciprocate the pan rectilinearly with respect to the axis of oscillation.

90 105 12. The apparatus described in claim 11, wherein means are provided to vary the points of suspension of the pan from the support whereby to alter the range of vertical reciprocation of the pan.

110 13. A concentrating apparatus comprising a pan, a settling baffle mounted in the pan in spaced relation to the sides thereof and defining with the sides a material receiving compartment, said baffle being also spaced from the bottom of the pan and defining therewith a material classifying passage of 115 tapered cross-sectional area, and means to oscillate the pan to shift the material in the compartment back and forth along the baffle whereby to cause the particles of material to pass beneath the baffle and through the tapered classifying passage at points corresponding to their respective sizes.

120 125 14. The apparatus described in claim 13, wherein the pan is substantially circular in form and the settling baffle is in the form of a ring.

15. The apparatus described in claim 13 wherein the pan is substantially circular in form and the settling baffle is in the form of a ring of varying depth.
- 5 16. The apparatus described in claim 13 wherein the pan is substantially circular in form and the settling baffle is in the form of a ring of varying depth, and wherein the material is charged into the pan sub-
- stantially at the point wherein the ring is 10 of greatest depth.
17. The apparatus described in claim 13 wherein the baffle is annular in form and wherein the pan is mounted for rotary oscillation about a substantially vertical axis. 15

In testimony whereof I hereunto affix my signature.

HOWARD E. PETRO.
